UNITED STATES PATENT OFFICE.

WILLIAM S. METCALFE, OF WORCESTER, MASSACHUSETTS, ASSIGNOR TO UNITED STATES ENVELOPE COMPANY, OF SPRINGFIELD, MASSACHUSETTS, A CORPORATION OF MAINE.

ENVELOP-MACHINE.

No. 923,679.

Specification of Letters Patent.

Patented June 1, 1909.

Application filed January 9, 1905. Serial No. 240,138.

To all whom it may concern:

Be it known that I, WILLIAM S. METCALFE, a citizen of the United States, residing at Worcester, in the county of Worcester and 5 Commonwealth of Massachusetts, have invented a new and useful Improvement in Envelop-Machines, of which the following is a specification, accompanied by drawings forming a part of the same, in which—

10 Figure 1 represents a plan view of that portion of an envelop machine which embodies my present invention, the mechanism for gumming and folding the envelop blank having been omitted. Fig. 2 is a side elevation of that portion of an envelop machine shown in sectional view on line 2—2, Fig. 1. Fig. 3 is a front elevation of that portion of the machine embodying my invention. Fig. 4 is a detailed and sectional view of the 20 gripping device for seizing the transparent patches to be applied to the openings in the envelop blank. Fig. 5 is a rear view of the swinging bar for controlling the action of the gripping device.

25 Similar reference letters and figures refer to similar parts in the different views.

My present invention relates to a mechanism for applying a transparent patch to cover an opening in an envelop blank in the position of the usual address in order to provide 30 a transparent panel capable of disclosing an address printed or written upon the inclosure contained in the envelop. The mechanism by which this result is accomplished is preferably embodied in an envelop machine by 35 which the operations of gumming and folding the envelop blank are performed.

In the accompanying drawings I have represented the mechanism embodying my 40 present invention as forming the component part of such an envelop machine, but for the purpose of rendering the mechanism embodying my invention more clear I have omitted the mechanisms for gumming and 45 folding the envelop blank. The gumming and folding mechanisms, however, are of the usual construction common in machines of this class and will be well understood by those conversant with envelop machines.

50 Referring to the accompanying drawings 1 denotes a table supported on suitable framework upon which the operative mechanism embodying my invention is mounted.

2; Fig. 1, is a top view of a pile of envelop

blanks, each of which is provided with an 55 opening 3 in the position of the usual address upon the envelop.

The shaded surface 4 denotes a gummed surface upon the edge of the back flap of the envelop, the shaded surface 5 denotes a 60 gummed surface upon the edge of the seal flap of the envelop, and the shaded surface 6 denotes a gummed margin around the opening 3. The gum upon these shaded surfaces 4, 5 and 6 is applied in the usual 65 and well known manner by means of a vertically reciprocating gumming die, not shown in the drawings. The application of the gum to the upper surface of the envelop blank causes the gummed blank to adhere 70 to the gumming die and to be raised by its upward movement, and in the elevated position of the blank a horizontally reciprocating carriage comprising the parallel rails 7, 7, is moved beneath the blank. The 75 gummed blank supported upon the carriage and having its rear edge engaged by upwardly projecting hooks 8, 8, is moved over the surface of a pressing table 9 upon the return movement of the carriage. The envelop 80 blank is then in position to receive a patch of transparent paper to cover the opening 3 and be attached to the gummed surface 6. The patches 10 of transparent paper are supported upon a feeding table 11 to which an 85 upward movement is given by means of the usual feeding apparatus employed in envelop machines to bring the uppermost blank in position to come in contact with a lifting mechanism which consists of a swinging arm 90 12, carried upon a rocking shaft 13 and supporting at its free end a suction device which 95 consists of a tube 14 capable of a slight sliding movement in a bracket 15 attached to the free end of the arm 12.

The tube 14 is normally held in its lowest position in the bracket 15 by means of a spiral spring 16 acting against the bracket 15, and a collar 17 attached to the tube, and its downward movement is limited by a collar 18 attached to the tube 14 above the bracket 15. The tube 14 is connected by a flexible tube 19 with a suction pump 20 consisting of a piston equipped cylinder actuated by an eccentric 21. When the tube 14 is in its normal position with its open lower end resting upon the uppermost blank of the pile 10 a vacuum will be formed in the tube

14 by the action of the suction pump 20, so that when the shaft 13 is rocked to raise the arm 12 the uppermost blank in the pile 10 will follow the suction tube and be lifted 5 into position to be seized by a gripping device consisting of a stationary jaw 22 projecting from the end of a hub 23 and a movable jaw 24 carried on the end of a rocking spindle 25 journaled in the hub 23 and in- 10 closed by a torsional spring 26 whose tension is applied to close the jaw 24 against the stationary jaw 22. The opposite end of the spindle 25 is provided with a crank arm 27 carrying a pin 27^a which is held by the torsional spring 26 in contact with the lower edge of a bar 28 which is pivotally attached 15 to the swinging links 29 suspended from the framework of the machine. The hub 23, carrying the gripping jaws 22 and 24 is attached to a sliding plate 30 connected by a link 31 with the crank arm 32, carried by a rotating shaft 33 by which a reciprocating motion is given to the gripping jaws 22 and 24 to advance them in position to seize the 20 end of the transparent patch which has been elevated from the pile 10 and a reverse movement draws the patch over the opening 3 in the envelop blank which has already been positioned above the pressing table 9 by the reciprocating movement of the carriage rails 7. The opening and closing of the gripping jaws is controlled by the movement of the bar 28 which is given a swinging movement on the links 29 by means of a link 34, pivotally connected to one end of the bar 28, and carrying at its opposite end a cam roll 35 which is actuated by a cam 36 on the shaft 33. A horizontally reciprocating motion is then given to the bar 28 while a rising 30 and falling motion is imparted to the bar by the swinging movement of the links 29. The crank arm 32 and cam 36 are relatively so timed that as the gripping jaws are moved forward to inclose the end of the elevated transparent patch the bar 28 will be raised to allow the torsional spring to close the movable jaw 24 against the fixed jaw 22 and remain closed during the reverse movement of the gripping jaws. When the patch has 40 been brought into position over the envelop blank the cam 36 allows the bar 28 to fall into contact with the pin 27^a, thereby reversing the action of the torsional spring 26 and opening the gripping jaws. As the transparent patch is drawn along by the gripping jaws to its position over the pressing table 9, it is supported upon the upper surface of a pair of horizontal blades 37 pivoted at one end upon posts 38.

50 Above the pressing table 9 is a hollow vertically reciprocating plunger 39 carried upon the lower end of a tubular spindle 40 which is connected by a flexible pipe 41, 41, with a piston equipped suction pump 42 actuated by an eccentric 43 to exhaust the air from the

hollow plunger 39. The plunger 39 is provided on its under surface with a series of holes 44 through which air is sucked to cause the adhesion of the transparent patch to the under side of the plunger, when the latter, by its downward movement, is brought into contact with the patch supported upon the blades 37. The vertical movement of the plunger 39 is controlled by a cam 45 on the shaft 33 through the arms 46 and 47 carried on a rock shaft 48. The arm 47 is pivotally connected by a link 49 with the spindle of the plunger to lift the latter while its downward movement is accomplished by a spring 50. When the adherence of the transparent patch to the under side of the plunger 39 is accomplished, the gripping jaws are opened by the swinging movement of the bar 28 against the crank pin 27^a and the blades 37 are separated by the movement of a wedge shaped block 51 between pins 52 projecting from the upper sides of the blades 37, one of which is shown in Fig. 3. The wedge shaped block 51 is attached to the outer end of a radial arm 53 carried on the rock shaft 48. The separation of the blades 37 allow the plunger 39 to complete its descent and carry the patch against the gummed surface 6 of the envelop blank and apply sufficient pressure to the patch to cause its firm adhesion to the blank. At this point the suction through the holes 44 is relieved by the reverse movement of the piston in the pump 42. The motion of the several parts above described are then reversed and the next reciprocating movement of the carriage rails 7 engages the rear side of the blank to which the patch has already been applied by means of a second pair of hooks 54, while the first pair of hooks 8 bring the next succeeding blank into position over the pressing table 9. The blank with the transparent patch already attached is moved by the hooks 54 forward over a rectangular opening 55 in a creasing block 56, through which it is pushed by a rectangular reciprocating plunger, not shown, in the usual manner common in envelop machines, thereby carrying the creased blank downward to a folding bed by which the operation of folding the flaps of the envelop are completed. Journaled in the framework of the machine is a main actuated shaft 57 to which power is applied and from which through appropriate connecting mechanism the movements of the patch controlling mechanism are operated in the manner above described. The rocking shaft 13 is actuated by a cam 58 through a connecting rod 59 and radial arm 60, while the carriage rails 7 are reciprocated in one direction by the cam 61 actuating the short lever 62 on a rock shaft 63 which carries the lever 64 connected by links 65 with the end of the carriage rails 7, and their motion is reversed by a spiral spring 66. The patch supporting blades 37 are brought together, after

having been separated by the wedge shaped block 51, by means of a spiral spring 67.

What I claim as my invention and desire to secure by Letters Patent is:—

5. 1. In an envelop machine, the combination with a pressing table for supporting an envelop blank, of means for holding a pile of patches near said table, a stationary support for a single patch above said table, and means 10 for transferring a single patch from said pile on to the opposite side of said support from said table.
2. In an envelop machine, the combination with a pressing table for supporting an envelop blank upon its upper surface, a reciprocating plunger arranged to descend upon said table, of means for holding a pile of patches near said table, a stationary support between said table and said plunger, 15 means for transferring a single patch from said pile on to the side of said support next to said plunger, and means for reciprocating said plunger.
3. In an envelop machine, the combination with a pressing table for supporting an envelop blank, means near said table for holding a pile of patches, a stationary support over said table for a single patch designed to be applied to said blank, means for 20 transferring a single patch from said patch holding means to the side of said support opposite to said table, supporting means for carrying said patch from said support into contact with said blank on said table, and means for applying pressure thereto.
4. In an envelop machine, the combination with a pressing table for supporting an envelop blank, of a support for a patch to be applied to said envelop over said pressing 25 table, means for holding a pile of patches near said support, means for transferring an individual patch in said pile on to said support, a reciprocating plunger, and means for holding said patch against the under surface 40 of said plunger.
5. In an envelop machine, the combination with a pressing table for supporting an envelop blank, and a reciprocating plunger, of a stationary table between said pressing 50 table and said plunger, separate means for bringing a patch on to said table designed to be applied to said blank, means for reciprocating said plunger, and means for moving said table out of the downward path of said plunger.
6. In an envelop machine, the combination with a pair of pressing surfaces, of means for moving an envelop blank having an opening therein between said pressing surfaces, 55 means for supporting a pile of transparent patches at one side of said pressing surfaces, means for selecting an individual patch from said pile, means for moving said selected patch between said pressing surfaces and in a line of movement at right angles to the line 60 of movement of the envelop blank, and means for applying pressure to the envelop blank and patch.
7. In an envelop machine, the combination with a pressing table for supporting an envelop blank, and a reciprocating plunger, of a table between said pressing table and said plunger, means for bringing a patch on to said table designed to be applied to said blank, means for reciprocating said plunger, 65 means for moving said table out of the downward path of said plunger, and means carried by said plunger for supporting said patch when said table is moved.
8. In an envelop machine, the combination with a pressing table for supporting an envelop blank and a reciprocating plunger, of a stationary table for supporting a patch above said pressing table in the path of said plunger, said stationary table comprising 80 pivoted members and means for separating said members after said plunger comes in contact with said patch upon said stationary table.
9. In an envelop machine, the combination with a surface for resisting the pressure upon an envelop blank, a reciprocating plunger for applying pressure to the envelop blank, a pair of reciprocating gripping jaws for drawing a patch over the envelop blank, 85 a pair of pivoted blades for supporting the patch, and means for moving said blades out of the path of the reciprocating plunger.
10. In an envelop machine, the combination with a pressing table for supporting an envelop blank and a reciprocating plunger, of means for supporting a patch above said table and in the path of said plunger, and means carried by said plunger to support said patch and carry it from said first mentioned supporting means into contact with said blank on said pressing table.
11. The combination of a table for supporting an envelop blank having an opening to receive a transparent patch, of means for moving a transparent patch to a position in registration with the opening in the envelop blank while supported on said table, a hollow reciprocating plunger for pressing the patch upon the envelop blank and having 100 openings in its pressing surface communicating with the interior of the plunger, and means for exhausting the air from said plunger.
12. The combination of a table for supporting an envelop blank, said blank having an opening to receive a transparent patch, a reciprocating plunger for pressing the patch upon the envelop blank, means for moving a transparent patch beneath said plunger, 105 means for imparting a downward movement to said plunger, and means for holding the transparent patch against the under surface of said plunger during its downward movement.

13. The combination with a pair of pressing surfaces for applying a transparent patch to an envelop blank and comprising a reciprocating plunger, means for transferring a transparent patch beneath said plunger, means for attaching said patch to the pressing surface of the plunger, means for releasing the patch from the transferring mechanism, and means for imparting a downward movement to said plunger.

14. In an envelop machine, mechanism for applying a transparent patch to an envelop blank provided with an opening to receive said patch and comprising the following instrumentalities in combination with a pair of pressing surfaces acting in the order

named, means for moving the envelop blank between a pair of pressing surfaces, means for transferring a transparent patch between the pressing surfaces and in registration with the opening in the envelop blank, means for adhering the patch to one of the pressing surfaces, means for releasing the patch from its transferring mechanism, and means for bringing the pressing surfaces together.

Dated this 28th day of December 1904.
